UNITED STATES PATENT OFFICE.

WILBER A. CARTER AND SABIN CROCKER, OF DETROIT, MICHIGAN, ASSIGNEES TO
GENERAL ELECTRIC COMPANY, A CORPORATION OF NEW YORK.

ELECTRICAL HEATING UNIT AND METHOD OF MAKING THE SAME.

1,233,183.

Specification of Letters Patent. Patented July 10, 1917.

Application filed June 5, 1916. Serial No. 101,771.

To all whom it may concern:

Be it known that we, WILBER A. CARTER and SABIN CROCKER, both citizens of the United States of America, residing at Detroit, in the county of Wayne and State of Michigan, have invented certain new and useful Improvements in Electrical Heating Units and Methods of Making the Same, of which the following is a specification, reference being had therein to the accompanying drawings.

The invention relates to electrical heaters and the method of making the same, and the heaters embodying my invention are more particularly designed for the heating of ovens to relatively low temperatures and where it is important to limit the temperature of the resistor element, but also applicable to other uses. One important use of such heaters is in the heating of ovens used for drying enamels and varnished articles, where highly-inflammable vapors are driven off; for if any portion of the heating element attains the ignition temperature of the gases an explosion will occur. Under the limitations just described, the resistor element must necessarily be provided with an extensive heat-radiating surface in order to develop sufficient heat for the entire oven without itself exceeding the temperature limit. It is also important to arrange the heater compactly, so as not to limit the capacity of the oven for receiving the work. To accomplish this result, we have devised a construction of resistor having a large heat-dissipating surface arranged within a relatively small area, without danger of short circuiting or exceeding the temperature limit in any portion thereof.

40 In the drawings:

Figure 1 is a side elevation of a mounted resistor of our improved construction;

Fig. 2 is a sectional perspective view of a portion thereof;

45 Fig. 3 is a cross section on line $x-x$ Fig. 1; and

Fig. 4 is an elevation of a sheet metal blank from which the resistor is formed.

Our improved resistor is preferably formed 50 from sheet metal and preferably from sheet iron or steel, as this has the double advantage of relatively high specific resistance and relatively great mechanical strength and rigidity. To secure the required amount of 55 surface within given space limits, the metal

is bent to have the adjacent portions thereof arranged in parallelism and closely spaced. There is, however, danger that when under heat these parallel portions will be warped, so as to come in contact with each other, 60 causing a short circuit. This difficulty we avoid by so fashioning the sheet-metal as to brace the same transversely of the plane thereof. We have also provided a mounting which holds the parallel portions in properly spaced relation. 65

Specifically, A is a sheet metal blank, which is slotted or cut transversely alternately from opposite sides thereof, to form a zigzag construction, having a series of parallel portions B B', etc. Each of these portions B B', etc., is stiffened, preferably by pressing thereinto one or more longitudinally-extending beads C. The portions D, which form the connections between adjacent portions B B', etc., are returnbent oppositely at opposite ends, so that said portions B B', etc., are arranged in parallel planes. E are insulator supporting strips, which are provided with a series of parallel slits extending inward from one edge thereof, 70 into which the portions B B', etc., are inserted, while the shoulders F formed by the returnbent portions D at the upper end of the resistor are adapted to rest upon the side of 75 the strip. G and H are suitable clips for securing the resistor to the strips E. 80

With the construction as described, the heating unit may be suitably mounted either adjacent to the side walls or the top or bottom of the oven. When in operation, the relatively large amount of exposed surface will rapidly dissipate the heat by both radiation and convection, thereby limiting the temperature rise in the resistor itself and also rapidly heating the air and surrounding objects. The cross-section is maintained uniform throughout the entire length, so that no portion will be heated in excess of 90 any other portion, and as there is equal access of air to all portions the rate of dissipation will be uniform. The bead or other transverse bracing so stiffens the sheet-metal as to avoid any possibility of adjacent parallel portions coming in contact with each other. 100

What we claim as our invention is:

1. The method of making a resistance element which consists in stamping from sheet metal an integral blank comprising success- 110

- sive parallel strips or ribbons connected at alternate ends, and bending the successive connecting portions in opposite directions to bring the element into the form of a grid 5 with the strips arranged edgewise to the plane of the element.
2. An electrical heating unit, comprising a resistor fashioned from sheet-metal to form a series of portions arranged in parallel planes and spaced from each other by less than the width thereof, said portions being longitudinally beaded to brace and stiffen the same and being connected to each other by returnbent portions alternately at 10 opposite ends thereof, a support for said resistor, comprising a plurality of insulator bars slotted to receive said parallel portions of the resistor, and clips for holding the resistor to said bars.
- 20 3. In an electrical heating unit, a resistor comprising a sheet-metal blank fashioned to form a series of portions arranged in parallel planes, said portions having returnbent transversely extending portions alternately arranged at opposite ends thereof and forming overhanging shoulders, and an insulator strip engaging the edges of said 25 portions in parallel planes and the shoulders formed by said returnbent portions.
- 30 4. In an electrical heater, a resistor formed of sheet-metal cut to form zigzag portions, being bent to arrange the latter in substantially parallel planes extending transversely of the original plane thereof, 35 and means for maintaining said parallel portions in spaced relation.
5. In an electrical heater, a resistor formed of sheet-metal cut to form zigzag portions in the plane of the sheet, being bent to arrange the latter in substantially 40 parallel planes transverse to the general plane of the resistor.
6. In an electrical heater, a resistor formed from a sheet-metal blank, fashioned to form a series of spaced portions in parallel planes with return-bent portions connecting the same adjacent to the alternate opposite ends thereof, and at opposite sides, and means for maintaining said parallel portions in spaced relation. 45
7. In an electrical heater, a resistor formed from a sheet-metal blank, fashioned to form a series of portions in parallel planes spaced from each other by less than the width thereof, with return-bent portions connecting the same adjacent to the alternate opposite ends thereof and at opposite sides, said portions being beaded to brace the same. 50
8. An electrical heater, comprising a resistor formed from sheet-metal, fashioned to form a series of sections arranged in parallel planes and spaced from each other by less than the width thereof, said sections being longitudinally beaded to brace and stiffen the same and connected by returnbent portions alternately at opposite ends thereof and at opposite sides, and a support for said resistor comprising an insulator having parallel slits therein for receiving 55 said parallel sections.
9. In an electrical heating unit, a resistor, formed of sheet-metal blank, fashioned to form a series of portions arranged in parallel planes, said portions being longitudinally beaded to brace and stiffen the same and having return-bent connecting portions alternately arranged at opposite ends thereof and on opposite sides. 60

In testimony whereof we affix our signatures.

W. A. CARTER.
SABIN CROCKER.
